LESLIE BUSWELL AND JOHN HAYS HAMMOND, JR., OF GLOUCESTER, MASSACHUSETTS;
SAID BUSWELL ASSIGNOR TO SAID HAMMOND.

PIPE ORGAN.

Application filed April 19, 1921, Serial No. 462,579. Renewed December 2, 1927.

Some of the objects of the present invention are to provide means for producing a glissando effect in an organ; to provide means for automatically varying the speaking length of an organ pipe to produce a glissando effect; to provide means for simultaneously and proportionately varying the speaking lengths of a plurality of organ pipes to produce a glissando effect; to provide means for manually producing a glissando effect in an organ; to provide means for producing a glissando effect in an organ synchronously with the playing of the organ; and to provide other improvements as will hereinafter appear.

In the accompanying drawings, Fig. 1 represents diagrammatically a control system for pipe organs embodying one form of the present invention; Fig. 2 represents a sectional elevation of a prime mover employed with the apparatus shown in Fig. 1; Fig. 3 represents a side elevation of a portion of the bellows control mechanism; Fig. 4 represents a front elevation of a modified form of the invention for manual control as applied to the mechanism shown in Fig. 1; Fig. 5 represents an elevation similar to Fig. 4 but with certain of the parts in another position; Fig. 6 represents a section on line 6—6 of Fig. 4; Fig. 7 represents a section on line 7—7 of Fig. 4; Fig. 8 represents a section on line 8—8 of Fig. 4; Fig. 9 represents a plan of the perforated roll control mechanism wherein a perforated music roll strip and a separate perforated glissando strip are arranged to be synchronously operated; Fig. 10 represents another form of perforated mechanism wherein a single strip of material is provided having two sets of control perforations for synchronously producing musical notes and glissando effect; and Fig. 11 shows a face view of one of the supporting members.

Referring to the drawings, one form of the present invention is shown in Fig. 1 in connection with three organ pipes 10, 11 and 12 arranged to be blown by any suitable means not shown, and each sounding a musical note different from the other two though bearing a definite musical relation thereto. The upper ends of the pipes 10, 11 and 12 are respectively encircled by cylindrical sleeves 13, 14 and 15 which are arranged to slide longitudinally with respect to the pipes 10, 11 and 12 and thereby vary the musical pitch of the

notes produced by the respective pipes in a predetermined manner.

For simultaneously moving the cylinders 13, 14 and 15, three racks 16, 17 and 18 are respectively made fast thereto and in mesh 60 respectively with three different sized pinions 20, 21 and 22 which are keyed or otherwise made fast to a shaft 23. The relative proportioning of the pinions 20, 21 and 22 is such that when the shaft 23 is rotated the cylinders or sleeves 13, 14 and 15 will each be moved a distance to vary the musical pitch of the notes produced by the respective pipes 10, 11 and 12 proportionately while still maintaining their musical relations. 65 The shaft 23 is supported in suitable fixed bearings 24, which in the present instance are carried by a main frame 25. Motion is transmitted to the shaft 23 by a pinion 26 fixed to the shaft 23 and meshing with a rack 27 which is arranged to be operated by a suitable prime mover 28.

For causing the rack 27 to be moved in the desired direction, the prime mover 28 is here shown as a pressure fluid motor comprising a cylinder 30, a piston 31 and a piston rod 32 which is in direct connection with the rack 27. The motor 28 is a double acting type having ports 33 and 34 respectively at opposite ends of the cylinder 30 which are controlled by similar mechanism including electrically operated valves 35 and 36. As the valves 35 and 36 are identical in construction and operation but one will be here described in detail, and only such parts of the other referred to as are necessary for a complete understanding of the structure. The port 33 is arranged to be controlled by the valve mechanism 35, the latter being in the form of a slide valve 37 arranged to move transversely of the port 33 and provided with two admission passages 40 and 41 of different sizes arranged to successively establish communication between the port 33 and an inlet port 42 which communicates 80 with a supply pipe 43 connected to any suitable source of compressed air 44.

The passages 40 and 41 are so arranged in the slide valve 37 as to first bring the passage of smaller dimension into register with the ports 33 and 42. The slide valve 37 is also provided with a passage 45 which normally establishes communication between the port 33 and an exhaust port 46. Thus, when one or the other of the ports 33 or 34 85

is thrown into communication with the source of pressure fluid the piston 31 will be shifted and the rack 27 moved in a corresponding manner to actuate the organ pipe cylinders 13, 14 and 15.

In order to shift the slide valve 37, it is preferably made of magnetic material and forms the core of a compound wound solenoid comprising a small winding 51 of 10 high resistance and a large winding 52 of low resistance. One end of the winding 51 is connected to a terminal 53, and one end of the winding 52 is connected to a terminal 54, while the other ends of the respective 15 windings 51 and 52 are connected to a common terminal 55. For convenience of explanation the corresponding terminals of the solenoid valve 36 are here identified as high resistance terminal 56, low resistance terminal 57 and common terminal 58. In this 20 valve 36, a pipe 60 serves as the air supply pipe and connects with the source 44. The valve 37 carries on its lower end an extension 61 of any suitable non-magnetic material 25 having a flange portion 62 arranged to abut the solenoid coils, and bearing against a relatively small spiral spring 63 which is held by and presses against a screw plug 64 threaded into the end of a tubular extension 65 fixed to the solenoid 50 and coaxial therewith. This extension 65 is provided with a bore 66 to provide a guide for free sliding of the member 61, and is also counter-bored to provide a guide for a 30 follower plate 67. A large spiral spring 68 is interposed between the plug 64 and the follower 67.

For respectively energizing the solenoid controlled valves 35 and 36, the piston rod 32 has a laterally extending rigid arm 70, fast to which is a bar 71 of insulating material. This bar 71 carries two contacts 72 and 73 and two strip contacts 74 and 75. The contact 72 is connected by a conductor 76 with the high resistance terminal 56 of the solenoid for valve 36. The contact 73 is connected by a conductor 77 with the high resistance terminal 53 of the solenoid for valve 35. The contact 74 is connected by a conductor 80 with the low resistance terminal 57 of the solenoid for valve 36, and the contact 75 is connected by a conductor 81 with the low resistance terminal 54 of the solenoid for valve 35. The 55 common return terminals 55 and 58 of the two solenoids are joined by conductors 82 and 83 to one pole of a battery 84, the other pole of which is connected to plate 85 of conducting material, which is supported by but insulated from the main frame 25.

For selectively operating the plurality of circuits above described, there are provided a plurality of rods of conducting material 60 here shown as thirteen in number and iden-

tified respectively by reference characters 86 to 98 inclusive, all of which have sliding contact engagement with the plate 85 to serve as contactors for completing at suitable times and in suitable relation the circuits controlled by the contacts 72, 73, 74 and 75. Under normal conditions none of the aforesaid rods 86 to 98 make contact.

For operating the respective rods 86 to 98, bellows 100 to 112 are provided, each bellows having a spring 113, which tends to hold its bellows in open position, and all of the said bellows being connected by pipes 114 to a common suction producing means 115. The arrangement is such that each rod is reciprocated by the opening and closing of its bellows. For automatically making selection of the aforesaid bellows 100 to 112, there are provided tubes 120 to 132 leading from the respective bellows to openings 133 to 145 provided in a tracker bar 147 over which a relatively long sheet 148 is arranged to travel at a constant rate by any suitable means, such as that provided in the usual player pianos. This sheet of 90 paper 148 is provided with a series of perforations 150 which are arranged to follow any desired curve.

In the drawings the cylinders or sleeves 13, 14 and 15 are shown in a central position, and in consequence the notes produced by the pipes 10, 11 and 12 will each have a definite pitch and are harmoniously related. The operation of the control system takes place as the sheet 148 moves across 100 the tracker bar 147. At first, with none of the perforations 150 in register with the tracker bar 147, all of the bellows 100 to 112 inclusive will be collapsed, because the air will have been drawn out by the suction 105 producing means 115, and consequently the contactor rods 86 to 98 will all be held out of contact with any of the circuit contacts. Now when the sheet 148 has moved sufficiently to bring the first of the series of perforations 150 over the tracker bar 147, air will enter the opening 139, pass through the tube 123 to the bellows 106, thus breaking the vacuum in that bellows and causing it to open under the action of the spring 113. 115 This forces the rod 92 to the right, as seen in Fig. 1, between the two contacts 72 and 73 and the apparatus remains as shown in Fig. 1 as long as the perforations 150 pass over the opening 139. As soon as the perforations 150 move over the opening 140, the bellows 106 will collapse again, returning the rod 92 to its initial position, while air will pass through the tube 127 to the bellows 107 which will open and throw rod 125 93 to the right to engage the contact 73. This closes the circuit through the conductor 77, terminal 53, high resistance winding 51, terminal 55, battery 84, plate 85 and rod 93, thus energizing the solenoid for 130

valve 35, so that the slide valve member 37 is drawn in against the action of the spring 63 until the member 61 contacts with the follower plate 67. This arrests the movement of the valve 37, because the current passing through the high resistance winding 51 is insufficient to overcome the action of the large spring 68. In consequence the valve member 37 moves the passage 41 into register with the inlet port 42 and port 33 so that compressed air enters the cylinder 30 above the piston 31 and causes the latter to move towards the other end of the cylinder, that is, downwardly as shown in Fig. 1. This is a relatively slow movement and carries 70 in the same direction until the contact 73 moves off of the rod 93. As soon as this occurs the circuit through the solenoid is broken and the core member 37 returns to its initial position under the action of the spring 63 and the motion of the piston 31 is stopped. The aforesaid downward movement of the piston 31 carries the rack 27 in the same direction, thereby rotating 25 the shaft 23 and causing the pinions 20, 21 and 22 to actuate the respective racks 16, 17 and 18 to shift the cylinders 13, 14 and 15 a certain definite amount, with the result that the notes of the pipes 10, 11 and 12 are modified a small amount but still remain in harmony.

As the perforations 150 move across the openings 141, 142, etc., the various rods 94, 95, etc. will be moved to the right in succession, each contacting in turn with the contact 73 to close the same circuit and open the valve 37 a small amount and the piston will be moved downward slowly. If, however, the perforations 150 should move across the tracker bar 147 to operate the rods 86 to 98 faster than the piston 31 moves, then the respective rods instead of making contact with the contact 73 will engage the strip contact 75, which closes the circuit through the low resistance winding 52 of the upper solenoid. This causes the valve member 37 to be moved downwardly with sufficient force to not only compress the spring 63 but also the spring 68 owing to the greater amount of current passing through the solenoid. As a result the large passage 40 is brought into register with the ports 33 and 42, thus allowing a large amount of compressed air to enter the cylinder 30 to move the piston 31 quickly downward.

If the perforations 150 traverse the paper 148 in the opposite direction and thereby cross the tracker bar 147 to the left, as seen in Fig. 1, then the rods 86 to 98 will be moved consecutively to the right, upwardly considered and engage either the contact 72 or the strip contact 74, depending upon the rapidity with which the perforations 150 move over the openings in the tracker bar 147. This action will cause the energization

of the lower solenoid controlling the valve 36 in the same manner as heretofore described, but causing the piston 31 to move in the opposite direction, namely upward, at a speed proportioned to the rate at which the perforations 150 cross the tracker bar 147. In this way the bar 71 is caused to follow the motions of the perforations 150 and, therefore, the rack 27 and the members 13, 14 and 15 are moved up and down a proportional amount, thus varying the notes of the pipes 10, 11 and 12 to produce the glissando effect.

In the form of the invention shown in Figs. 4 to 8 inclusive, the manual control mechanism is shown applied to the tracker bar 147 which is mounted in vertical supports 151 and 152 and has its holes or openings 133 to 145 respectively arranged to be opened and closed by cover plates 153 to 165 inclusive. These plates 153 to 165 are each provided with a substantially elliptical hole 166 through which there passes a bar 167 having a cross section which is substantially oval, the construction being such that each of the plates 153 to 165 can oscillate upon the bar 167 through a small angle. The bar 167 is rotatably mounted in the supports 151 and 152 and is provided with a lug 168, which rests against a stop 170 when in the position shown in Fig. 4, and against a stop 171 when in the position shown in Fig. 5. A spring 172 is secured to the support 151 and operates to hold the lug 168 against the stop 171 at suitable times. A handle 173 is fast to the bar 167 for the purpose of manually turning the bar 167 through a little more than a half revolution.

The plates 153 to 165 inclusive are respectively held normally closing the tracker bar 147 openings 133 to 145 by means of springs 174-186 inclusive, the said springs being rigidly attached at one end to a fixed rod 187 when the free ends thereof bear against the respective plates 153 to 165.

For actuating the respective plates 153 to 165, a rod 190 is provided, one end of which is rigidly secured to the support 151 and the other end of which is rigidly supported in a fixed member 191. Freely movable upon this rod 190 is a tube 192 preferably square in cross-section and provided at one end with a laterally disposed cam face 193 having a rounded end portion arranged to engage the respective plates 153 to 165 in its path of movement. A pin 194 is fixed to the tube 192 adjacent its other end and rides in a slot 195 formed in an arm 196 which is pivoted at 197 to a fixed part 198 and terminates in a handle 200.

In the operation of this form of the invention the arm 196 is operated manually by means of the handle 200 thereby shifting the tube 192 to the right or left as desired. This movement causes the cam 193 to move

from one of the plates 153 to 165 to another, thereby causing the released plate to close its tracker bar opening and the successively operated plate to uncover its tracker bar opening. Assuming plate 159 is lifted, as shown in Figs. 6 and 7, air has free access to the opening 139 and thereby traverses the tube 126 and operates the bellows 106 in the manner heretofore described. Thus as the cam 193 moves from one end of the tracker bar 147 to the other, it successively moves the plates 153 to 165 away from the tracker bar 147 thereby uncovering the ports or openings 133 to 145 in succession as desired.

It is therefore evident that this operation is similar to the automatic construction where the holes 150 in the strip of paper 148 pass over the tracker bar 147 and operate the pipe cylinders 13, 14 and 15. In the manual operation the pipe cylinders 13, 14 and 15 will follow the motion of the handle 200 and produce the desired glissando effect.

In the manual operation of the instrument the handle 173 is in the position shown in Fig. 4 with the lug 168 resting on the stop 170 and the plates 153 to 165 are in position to cover the tracker bar openings. When it is desired to change from the manual operation to the automatic operation, the handle 173 is thrown over to bring the lug 168 against the stop 171, where it is held by the spring 172 and the plates 153 to 165, which are turned by the bar 167, assume the position shown in Figs. 5 and 8, thereby leaving the face of the tracker bar 147 free for the movement of the perforated paper 148.

In Fig. 9 of the drawings the perforated strip 148 for controlling the glissando effect is shown mounted upon feed rolls 201 and 202 which are journalled in a suitable framework 203, the roll 202 being arranged to be driven by a rotatable shaft 204 from a source of power. This framework 203 also carries the music roll perforated note sheet 205 by means of which the organ is played, the said sheet 205 being mounted upon feed rolls 206 and 207. The roll 207 is fast to the driven shaft 204 and the construction is therefore such that the two sheets 148 and 205 are synchronously driven to simultaneously perform their respective functions. The note sheet 205 passes over the usual tracker board 208, which, in the present construction, has as an extension thereof the tracker board 147 for the glissando control strip 148. The tracker board 208 is provided with the customary openings 210 to 222 inclusive, the number of such openings corresponding to the number of organ pipes, and those here shown being only illustrative as will be understood. The note sheet 205 is provided with perforations 223 which register in a predetermined manner with the tracker board openings in a well known manner. Tubes 224 to 236 in-

clusive lead from the respective openings 210 to 222 to the pneumatic mechanism (not shown) and from such mechanism pipes 237, 238, 239, etc. are in communication with the respective organ pipes. Thus the pipes 10, 11 and 12 are operated by the respective pipes 237, 238 and 239 through the initial opening of the tubes 224, 225 and 226 under control of the tracker board openings 210, 211 and 212.

In the modification shown in Fig. 10 a single note sheet 250 is provided having at one side playing perforations and at the opposite side glissando control perforations, both of which are identified by the respective reference numerals heretofore employed, namely 150 and 223 in order to avoid confusion. Single feed rolls 251 and 252 serve to feed the sheet 250 across the common tracker board 253, one of the rolls being fast to a driven shaft 254 journalled in the frame 255. The operating openings and pipes are the same as already described and are therefore numbered the same.

Thus in the forms shown in Figs. 9 and 10 the strip of perforated material for controlling the glissando effect is operated synchronously with the organ playing perforated strip, the two strips operating together in a predetermined manner so that the glissando effect takes place when and where desired.

While but two of the many forms in which this invention is used have been here shown, it is to be understood that the invention is not limited to any specific construction, but might be applied in various forms without departing from the spirit of the invention or the scope of the appended claims.

Having thus described our invention, we claim:

1. In a musical instrument, an organ pipe and means cooperating with said pipe to produce a glissando effect, including a tracker bar and a perforated strip of material.

2. In a musical instrument, a plurality of organ pipes, and means cooperating with said pipes to simultaneously produce a glissando effect in said pipes, including a tracker bar and perforated strip of material.

3. In a musical instrument, a plurality of organ pipes, and means for simultaneously and proportionately varying the speaking lengths of said pipes to produce a glissando effect.

4. In a musical instrument, a plurality of organ pipes, and means for simultaneously and proportionately varying the speaking lengths of said pipes to produce a glissando effect, including a plurality of movable cylinders mounted respectively on said pipes.

5. In a musical instrument, a plurality of organ pipes, means for simultaneously and proportionately varying the speaking

lengths of said pipes to produce a glissando effect, and means for controlling the glissando effect in a predetermined manner.

6. In a musical instrument, a plurality of 5 organ pipes, means for simultaneously varying the speaking lengths of the respective pipes to produce a glissando effect, and means for controlling the glissando effect in a predetermined manner.
- 10 7. In a musical instrument, a plurality of organ pipes, means for simultaneously varying the speaking lengths of the respective pipes to produce a glissando effect, and means including an electrically operated 15 mechanism for controlling the glissando effect in a predetermined manner.

8. In a musical instrument, a plurality of organ pipes, means for varying the speaking lengths of the respective pipes to produce a 20 glissando effect, and means including a tracker board mechanism for controlling the glissando effect in a predetermined manner.

9. In a musical instrument, a plurality of 25 organ pipes, means for varying the speaking lengths of the respective pipes to produce a glissando effect, and means including a tracker board and a strip of material perforated in a predetermined manner for controlling the glissando effect in a 30 predetermined manner.

10. In a musical instrument, a plurality of organ pipes, means for varying the sounding 35 lengths of the respective pipes to produce a glissando effect, electrically operated means for controlling said varying means, means including a tracker board for actuating said electrically operated means, and a strip of material arranged to control said tracker board means in a predetermined manner.

40 11. In a musical instrument, a plurality of organ pipes, means for automatically sounding said pipes to produce a tune, and means operating in conjunction with said sounding means to produce a glissando effect 45 with said pipes, each of said means includ-

ing a movable strip of material perforated in a predetermined manner.

12. In a musical instrument, a plurality of organ pipes, means for automatically sounding said pipes to produce a tune, and means including a plurality of simultaneously movable sleeves mounted respectively on said pipes for producing a glissando effect.

13. In a musical instrument, a plurality of 50 organ pipes, means including a sheet having a plurality of perforations arranged in a predetermined manner for sounding said pipes to produce a tune, and means including a plurality of movable sleeves mounted 60 respectively on said pipes for producing a glissando effect.

14. In a musical instrument, a plurality of 65 organ pipes, means including a sheet having a plurality of perforations arranged in a predetermined manner for sounding said pipes to produce a tune, and means also including a sheet having a plurality of perforations arranged in a predetermined manner for producing a glissando effect with 70 said pipes.

15. In a musical instrument, a plurality of 75 organ pipes, means including a sheet having a set of perforations arranged in a predetermined manner for sounding said pipes to produce a tune, means also including another set of perforations arranged in a predetermined manner for producing a glissando effect with said pipes, and means for operating said sets of perforations in synchronization.
